UNITED STATES PATENT OFFICE

ANDREW H. BAKKEN, OF EDGEWOOD PARK, PENNSYLVANIA, ASSIGNOR TO WESTINGHOUSE ELECTRIC & MANUFACTURING COMPANY, A CORPORATION OF PENNSYLVANIA

CIRCUIT BREAKER

Application filed March 24, 1921. Serial No. 455,219.

My invention relates to circuit breakers and particularly to the mechanism by which circuit breakers are automatically opened under predetermined conditions.

5 The object of my invention is to provide a mechanism whereby the automatic tripping operation is effected with a high degree of efficiency.

10 My construction permits of the use of a wider air-gap between the movable core member that actuates the tripping rod, and the stationary core member or pole piece, that magnetically attracts the movable core member.

15 I accomplish the foregoing by the provision of mechanism that has a counter-balancing effect on the movable tripping elements and thereby assists the stationary magnetizable member in overcoming the inertia 20 of such parts. This construction permits the employment of a comparatively wide air-gap, which results in a heavier impact by the movable tripping members.

25 The Fig. 1 of the accompanying drawing is a view, partially in side elevational and partially in section, of the tripping mechanism of a circuit breaker having my invention embodied therein, and

30 Fig. 2 shows an arrangement of circuits whereby the operation of certain of the automatic tripping apparatus is controlled.

35 A panel 1 supports a handle 2, an automatically releasable lever 3, and electromagnetic coils 4, 5 and 6, in the usual manner.

40 A latch 7 is provided for normally maintaining the tripping lever 3 and the manually-operated handle 2 in locked relation. An operating rod 8 carries a movable core member 9 which is adapted to be moved upwardly under the influence of a stationary magnetizable member or pole piece 10, which is energized by the electromagnetic coil 4. This movement of the rod 8 trips the latch 7 to permit the lever 3 to move independently of the manually-controlled handle 2.

45 The rod 8 has sliding engagement with the pole piece 10 and, in addition to the movable core member 9, has an auxiliary core member 11 secured at its lower end movable in relation thereto. The core member 11 is shown

as being built up of end plates 12 and 13 and steel laminations 14 held together by means of rivets (not shown) which pass through the end plates and the laminations. A bracket 15 serves to support the core member 23 within which the auxiliary electromagnetic members 5 and 6 are carried and also serves as a guide for the lower end of the rod 8. The rod 8 passes through a hole in a bar 16, the ends of which extend into slots 17 and 18 in the bracket 15 in such manner as to have vertical movement therein.

50 The rod 8 extends through a bushing 19, and is provided with a reduced portion 20 which extends into an auxiliary movable core member 11. A nut 21 is screwed to the lower end of the rod 8 and serves to clamp the core member 11, bushing 19, and bar 16 in their proper relative positions on the rod 8 in such manner as to have the core member 11 movable thereon to enable it to properly seat itself on the core member 23.

55 A compression spring 22, carried within the casting 23, is so calibrated that it will be compressed by the weight of the operating rod 8 and the parts carried thereby. The position of the spring may be adjusted by means of a set screw 24 to so position it that the weight of the moving members will compress it sufficiently to permit such members to reach their normally retracted position and, at the same time have sufficient tension to substantially counter-balance the weight of the movable parts when they are in retracted 60 position.

65 In the application of the invention just described, the coils 4 and 5 are normally constantly supplied, through a transformer 26, with current from the main circuit 27, and 70 exert opposing forces on the movable core members 9 and 11, respectively.

75 When a predetermined abnormal condition occurs in the main circuit, the coil 6 is energized through the closing of its circuit 28 by a relay 29, and tends to set up a flux that is counter to the flux of the coil 5, thus neutralizing the effect of the coil 5 and permitting the movable core member 9 to travel upward under the influence of the coil 4 and the pole 80

piece 10, carrying with it the operating rod 8 and tripping the latch 7.

It will be observed that the spring 22 acts as a counter-balance to the weight of the rod 8 and the parts carried thereby. This construction permits the use of a comparatively large number of ampere turns in the coil 4, because of the wide air-gap between the movable core member 9 and the pole piece 10 and by reason of the assistance rendered by the spring 22 in overcoming the inertia of the movable members. A further advantage resides in the fact that the movable members are enabled to travel a greater distance before the operating rod 8 comes into engagement with the locking member 7, and a more effective blow is secured by reason of the additional momentum.

Various modifications may be made in the construction without departing from the spirit of the invention, as defined in the accompanying claims.

I claim as my invention:

1. In combination, a stationary magnetizable core member, a movable core member normally in spaced relation thereto, an operating rod for carrying the movable core member, a guide for the rod, an auxiliary stationary core member, an auxiliary movable core member secured to the operating rod adjacent the lower end thereof in position to be acted upon by the auxiliary stationary core member, a spring in position to be compressed by the operating rod when said rod is in retracted position, and means for neutralizing the magnetic attraction between the auxiliary movable core member and the auxiliary magnetizable core member.

2. In combination, a stationary magnetizable core member, a movable core member associated therewith, a rod for supporting said movable core member that is movable therewith, an auxiliary stationary core member, an auxiliary movable core member supported on the rod in spaced relation to the first said movable core member, whereby the rod is moved when either of the movable core members is actuated by the associated stationary core member.

3. In combination, a stationary magnetizable core member, a movable core member associated therewith, a rod for supporting said movable core member that is movable therewith, an auxiliary stationary core member, an auxiliary movable core member pivotally supported on the rod, whereby the rod is moved when either of the movable core members is actuated by its associated stationary core member.

4. In combination with a releasable controlling lever, of a latch for said lever, a rod for releasing said latch, two independent core members attached to the rod, a magnetizable member associated with each of said core members and a biasing means for exerting a

force on said rod for moving it toward said latch.

5. In combination with a releasable controlling lever, of a latch for said lever, a rod for releasing said latch, two independent core members supported in relative fixed position on the rod, one in pivotal relation thereto, a magnetizable member associated with each of said core members and a biasing means for exerting a force on said rod for moving it toward said latch.

6. In combination with a circuit-interrupter latching mechanism, of a rod for releasing said mechanism, two stationary core members in spaced relation to each other, two movable core members independently attached to said rod in such manner as to be respectively associated with a stationary core member, two series-connected windings differentially associated with said core member, a biasing means for applying a force to said rod against the retaining force of one of said windings and a third winding for rendering the retaining force of said winding ineffective.

7. In combination with a circuit-interrupter latching mechanism, of a rod for releasing said mechanism, two stationary core members, two movable core members attached to said rod, one in pivotal relation thereto, two windings associated with said core members, one for preventing and the other for causing movement of said rod and a third winding for rendering the one winding ineffective for preventing the movement of said rod.

8. In combination, a pair of windings each having a stationary core member associated therewith, a movable member, a pair of core members each attached to said movable member, one being in pivotal relation thereto, a biasing means for actuating said movable member and an additional winding for rendering one of said pair of windings ineffective under certain predetermined conditions.

9. In combination, a pair of windings each having a stationary core member associated therewith, a movable member, a pair of core members each attached to said movable member, one being in pivotal relation thereto, a biasing means for actuating said movable member, adjustable means for changing the effective force of the biasing means and a third winding for rendering one of said pair of windings ineffective under certain predetermined conditions.

In testimony whereof, I have hereunto subscribed my name this 18th day of March, 1921.

ANDREW H. BAKKEN.
